UNITED STATES PATENT OFFICE.

CHARLES G. BURTON, OF PERU, INDIANA.

SOCKET FOR ELECTRIC LAMPS.

No. 881,297.

Specification of Letters Patent. Patented March 10, 1908.

Application filed March 14, 1907. Serial No. 362,269.

To all whom it may concern:

Be it known that I, CHARLES G. BURTON, a citizen of the United States, residing at Peru, in the county of Miami and State of Indiana, have invented new and useful Improvements in Sockets for Electric Lamps, of which the following is a specification, reference being had to the drawings, forming a part thereof.

The purpose of this invention is to provide an improved socket for electric lamp bulbs, the specific purposes being to facilitate the engagement of the shell with the cap and its disengagement therefrom and avoid the danger of accidental disengagement; to reduce the liability of short circuiting when in the absence of the lamp a foreign conducting body is intruded into the socket when the key is turned on, and to simplify and reduce the cost of construction.

It consists of the features of construction for these purposes which are described and shown as set out in the claims.

In the drawings:—Figure 1 is an axial section of the cap and shell of a lamp socket embodying these improvements. Fig. 2 is an axial section of the insulating base elements and the part mounted thereon at the line 2—2 on Fig. 4. Fig. 3 is a similar section at the line 3—3 on Fig. 4. Fig. 4 is a section at the line 4—4 on Figs. 2 and 3. Fig. 5 is a perspective view of a catch device which is made rigid with the cap for connecting the shell thereto. Fig. 6 is a detail section at the line 6—6 on Fig. 3. Fig. 7 is a detail section of the porcelain base at the line 7—7 on Fig. 4.

The structure shown in the drawings comprises a shell, 1, which is connected with the cap, 2, 3 being a snap device for connecting the two parts, 1 and 2, together. The shell comprises an interiorly threaded hub or central collar portion 2^a, with which the remainder of the shell is rigid. The snap device, 3, consists of a ring or collar portion, 3^a, having two oppositely projecting spring arms, 3^b, each terminating in a catch nose, 3^c. The snap device is made rigid with the cap by brazing or otherwise rigidly securing the ring or collar portion, 3^a, on to the hub or collar, 2^a, of the cap, the two spring arms, 3^b, extending up within and substantially conforming to the shape of the bell portion, 2^b, of the cap, the catch noses, 3^c, registering with and being in a position to protrude through apertures, 2^d, in the marginal flange of the cap. The shell, 1, has the usual notch,

1^a, for the stem of the key and has also two oppositely situated apertures, 1^b, which are adapted to register with the apertures, 2^d, of the cap when the larger end of the shell is inserted within the marginal flange of the cap. When thus inserted with the apertures, 1^b and 2^d, registering, it will be seen that the catch noses, 3^c, protruding through the apertures of both the registered parts 60 will retain them securely in engagement. Accidental disengagement is prevented by the form of the under side of the catch noses, 3^c, said noses having the under edge tapered for a distance, 3^e, and then extending 70 straight,—that is, substantially at right angles to the axis of the socket,—for the remaining portion, 3^f, of said edge, said portion, 3^f, being long enough to extend out through the thickness of the shell when the 75 latter is inserted, so that the lower edge of the notch, 1^b, of the shell will encounter said straight portion, 3^f, upon any pull tending to withdraw the shell from the cap. The end of the nose, 3^c, projects far enough out from 80 the cap so that it may be pressed by the finger of the operator inward a distance which will bring the slant portion, 3^e, of the under edge of the nose in the path of the edge of the notch, 1^b, so that the shell upon being 85 pulled out will crowd the nose back and escape past it. The upper or outer edge, 3^g, of the nose may be slanted for its entire length so that the shell may be inserted without any attention to the catch noses 90 which will be crowded back by encounter of the lower edge of the entering shell and will spring into the apertures when they reach the catch noses. Any desired number of 95 spring arms or fingers, 3^b, may be provided projecting from the collar, 3^a, a corresponding number of registering apertures being provided in the cap flange and shell. Two is ordinarily sufficient for secure engagement of the parts, and is ordinarily preferable to a 100 larger number because the operator cannot readily with one hand press in more than two for disengaging the shell.

4 and 5 are respectively the lower and upper parts of the insulating element or base. 105 They are secured together by bolts, 4^x. Upon the upper part, 5, there is mounted rigidly the threaded lamp-engaging contact sleeve, 6, through which electrical connection is made in a familiar manner w^t one terminal of the carbon filament of the lamp not shown. Both of the contact-shell-securing

screws, 4^a, also secure the circuit-connection piece, 6^c, through which the binding screw, 6^d, is set and exposed at the side of the insulating base. The switch chamber is formed by a cavity, 5^a, in the lower side of the upper part and a cavity, 4^a, in the upper side of the lower part of said insulating element. An aperture, 5^b, leads through the upper wall of the switch chamber into the cavity of the contact shell, 6, and a spring metal loop, 7, is secured by a screw, 8, to the said upper part, 5, having one of its limbs exposed in the switch chamber and the other exposed in the cavity of the contact shell, 6, and intermediately extending through the aperture, 5^b. At the normal position of this spring loop it protrudes up into the cavity of the shell, 6, its limb in the switch chamber lying close up against the under side of said upper wall of said switch chamber. Its resiliency permits it to be depressed into the switch chamber to a position shown in dotted line in Fig. 2. The switch chamber communicates from the cavity, 4^a, of the lower part laterally through an aperture, 4^b, with the outer surface, and the binding screw, 9, for one of the inleading wires is set into a metal connection piece, 10, which extends in through said aperture and is secured to the lower part, 4, of the insulating base at the center thereof by the screw, 11. The same screw binds firmly on to the connection piece, 10, the spring contact piece, 12, which is folded in a loop or bow, 12^a, and has the upper end reflexed overhanging the lower end and fastening screw, 11, extending across the direction of the stem of the key, 13, which carries the tumbler block, 14, which may be of any customary form and connected in any customary manner with the stem for rotation therewith with a certain amount of play thereon serving well understood purposes. The tumbler block, 14, as usual is oblong and at the off position of the key extends horizontally. The key is journaled in the opposed faces of the two parts, 4 and 5, of the insulating block and in addition has bearing in the two arms of the U-shaped bearing piece, 15, which is also secured by the screw, 11, its two arms embracing the upper limb of the spring contact piece, 12^a. Said upper arm of the spring contact piece normally presses elastically up against the tumbler block, 14, and bears against one of its longer sides when the key is at "off" position, as shown in dotted line in Fig. 2, yielding downward when the key is turned to "on" position,—with the longer dimension of the block extending vertically or in the direction of the axis of the socket,—as shown in full line in said Fig. 2. When there is no lamp in the socket, the block, 14, is not in contact with the contact piece, 7, even when the key is turned to "on" position, because said contact piece, 7, normally stands as shown in

Fig. 2, with its lower limb up against the under side of the upper wall of the switch chamber which is not reached by the end of the tumbler block. When, however, the lamp is screwed fully into the contact shell, 6, it forces down the contact piece, 7, until the limb is pressed upon the upper end of the tumbler block, 14, when the latter is in full-line position shown in Fig. 2; but the insertion of the lamp does not carry the contact piece, 7, down far enough to reach the block when it is in dotted-line position shown in said figure. It will be understood from this description that there is a double gap in the circuit connections formed by the parts mounted on the insulating base, said gap being between the tumbler block, 14, and the contact piece, 7. Part of the gap is closed by turning the tumbler block from dotted line to full line position,—that is, from "off" to "on" position of the key,—and the remainder of the gap is closed by screwing in the lamp so as to force the contact piece down into the tumbler block, but neither one of these operations without the other will close the gap so as to bring the lamp into circuit.

I claim:

1. In an electric lamp socket, in combination with an insulating base, electric circuit connections mounted thereon for connecting the two carbon filament terminals of the lamp, said circuit connections having a gap and a switch device in such gap, the switch device being adapted to only partly close the gap by rotation from "off" to "on" position, one of the elements of said connections being movable to complete the closing of the gap and being mounted for such movement by the insertion of the lamp. 95
2. In an electric lamp socket, in combination with an insulating base, electric circuit connections mounted on such base comprising a switch device and a key for rotating it, said connections having a gap which is only partly closed by the switch device, one element in said connections being a piece which yieldingly opposes the insertion of the lamp and which is moved by such insertion for completing the closing of the gap. 105
3. In an electric lamp socket, in combination with an insulating base, means for connecting the lamp therewith; electric circuit connections mounted on the insulating base for connecting the two terminals of the lamp filament, said circuit being formed with a gap, and a switch device in such gap, the connection at one side of said gap being normally out of position for connecting with the switch device and being exposed in the path of insertion of the lamp for movement thereby into position for contact with the switch device. 115
4. In an electric lamp socket, in combination with an insulating base and means for mounting the lamp thereon; electric circuit 120

connections mounted on the insulating base for connecting the two terminals of the lamp filament, and said circuit connections having two parts which are movable to complete the circuit, one of said parts being a switch device provided with a key for rotating it, the other of said parts being exposed in the path of insertion of the lamp for movement by such insertion in direction for completing the 10 circuit.

5. In an electric lamp socket in combination with an insulating base, means for securing the lamp thereto; electric circuit connections mounted on the base for connecting the 15 two terminals of the lamp filament, said circuit connections comprising two parts which are movable for completing the circuit, one of said parts being a switch device having a key for operating it, the other of said parts 20 being a resilient contact piece for making one of the lamp contacts and being mounted so as to be normally out of circuit-completing positions at all positions of the switch device and being exposed in the path of insertion of 25 the lamp and yieldingly resisting such insertion and adapted to be moved thereby into circuit-closing position.

6. In an electric lamp socket, in combination with the shell and cap having registering apertures at their interlapping margins and a spring catch device mounted on one of 30 said parts having a catch nose which snaps through the corresponding apertures of said two parts when they are registered.

35 7. In an electric lamp socket, in combination with a shell and cap having each two oppositely situated apertures adapted to register respectively with the corresponding apertures of the other part; two oppositely 40 situated spring catch devices mounted on one of said parts having catch noses which snap through the corresponding apertures of said parts when they are registered for securing them together.

45 8. In an electric lamp socket, in combination with a shell and base adapted to telescope one within the other for engagement, each of said parts having at their marginal portions which are interlapped when they 50 are so telescoped corresponding apertures adapted to register; spring catch devices mounted on one of said telescoped parts having catch noses which snap through the registered apertures respectively for securing the 55 two parts together, said catch noses having their edges which are encountered by the

edges of the apertures on the opposite part when said telescoping elements are pulled in direction for disengagement sloped or beveled at the outer portion and extending substantially directly across said encountering edges at the inner portion, said catches being exteriorly accessible when engaged for springing them to a position for encounter of the beveled portion of said edges in the disengaging movement.

60 9. In an electric lamp socket in combination with a shell and cap adapted to telescope for engagement, said telescoped parts having corresponding apertures adapted to register 70 when they are telescoped; a spring catch device mounted on the cap having catch noses for snapping through said apertures of both parts for securing them together.

75 10. In an electric lamp socket in combination with a shell and cap adapted to telescope for engagement, said telescoped parts having corresponding apertures adapted to register when they are telescoped; a spring catch device mounted on the cap having catch noses 80 for snapping through said apertures of both parts for securing them together, said catch noses being sloped or beveled at their outer portion and having a square shoulder at the inner portion on the side toward the cap for 85 positively securing the shell against disengagement.

90 11. In an electric lamp socket in combination with a shell and cap adapted to telescope for engagement, said telescoped parts having corresponding apertures adapted to register 95 when they are telescoped; a spring catch device mounted on the cap having catch noses for snapping through said apertures of both parts for securing them together, said catch 100 noses being sloped or beveled at their outer portion and having a square shoulder at the inner portion on the side toward the cap for positively securing the shell against disengagement, said catch noses being long enough to protrude out through the outer of said telescoped elements for pressure thereon to spring them in to carry said shoulders out of engaging position.

105 In testimony whereof, I have hereunto set my hand at Peru, Ind., this 2d day of March, 1907.

CHAS. G. BURTON.
